UNITED STATES PATENT OFFICE.

CARL HENDERSON, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

COMPENSATING CYLINDER FOR PRINTING-PRESSES.

1,106,508.

Specification of Letters Patent.

Patented Aug. 11, 1914.

Application filed October 7, 1912. Serial No. 724,257.

To all whom it may concern:

Be it known that I, CARL HENDERSON, a citizen of the United States, residing at Oak Park, in the county of Cook and State 5 of Illinois, have invented certain new and useful Improvements in Compensating Cylinders for Printing-Presses, of which the following is a specification.

My invention relates to mechanism which 10 may be used in connection with a printing couple having as one member a rotatable impression cylinder.

In printing presses as heretofore constructed considerable difficulty has been experienced in obtaining exact coöperation between the impression cylinder and the form carrying member with which the said cylinder operates. The impression cylinder is ordinarily provided with bearers on its 20 ends, these bearers engaging bearers on the sides of the form carrying member. It will be evident that in this construction of printing press there are three elements controlling the relative movement of the impression cylinder and the form carrying member: First, the gearing which actuates the cylinder and the form carrying member; second, the engagement between the bearers; and, third, the paper which engages the 25 impression cylinder on one surface and the form on the other. If there is not exact correspondence between these various elements, the printing is apt to be imperfectly performed, and the form is subjected to undue 30 wear. In order to obtain perfect coöperation it is now necessary to use great care and expend considerable time in preparing a printing press for the printing operation.

The chief cause of the difficulty heretofore experienced in properly operating printing presses of the type which I have mentioned has resided in the lack of perfect coöperation between the impression surface and the form, since it is necessary to 40 specially prepare the surfaces of both of these elements whenever the press is made ready to print, while, on the other hand, if the press is properly constructed in the beginning, the proper coöperation between the 45 gearing and bearers is always maintained.

It is the object of my invention to overcome the difficulties which have been mentioned above, and, in general terms, I accomplish this result by means of allowing a

slight amount of relative movement between 55 the impression surface and the form so that any irregularities or lack of perfect coöperation between these elements will be compensated for by the automatic adjustment of said surface so that it has perfect coöperation with the form, thereby satisfactorily and perfectly performing the printing operation. These and other advantages of my invention will be more readily understood by reference to the accompanying drawings, 60 65 which show a preferred embodiment of my improvements, and in which—

Figure 1 is a fragmentary side elevation and partial sectional view of a printing press showing the impression cylinder and 70 reciprocatory bed; Fig. 2 is a vertical section taken on the line 2—2 of Fig. 1; Fig. 3 is an enlarged fragmentary side elevation of a portion of the impression cylinder showing the compensating mechanism; 75 Fig. 4 is a horizontal section taken on the line 4—4 of Fig. 3; and Fig. 5 is an enlarged horizontal section taken on the line 5—5 of Fig. 1.

The printing press is provided with the 80 reciprocatory bed 10 operating on the rollers 11—11, according to the well-known system. Carried by the bearings 12—12 is a shaft 13, to which are keyed the bearers 14 which engage the bearers 15 on the sides of 85 the bed 10. Each of the bearers 14 is provided with a bearing surface 16, these bearing surfaces being engaged by the ends of the impression cylinder 17, as clearly shown in Fig. 2. The cylinder 17 is provided with 90 the usual gripper rod 18 carrying the grippers 19. One end of the gripper rod 18 extends through the stud 20 carried by the cylinder 17. This stud projects through a suitable aperture in the bearer 14, this aperture being somewhat larger than the stud 20 95 in order to allow relative movement of the cylinder 17 and the bearers 14.

As clearly shown in Figs. 1, 3 and 4, the cylinder 17 is provided with a cylinder 100 drive stud 21 rigidly fastened to the cylinder and projecting into the aperture 22 in the bearer 14. This stud 21 is provided with adjusting screws 23—23, which may be rotated to provide the desired amount of 105 lost motion between the bearers 14 and the cylinder 17, it being evident that on rotation of the bearers 14 the end of the aperture 22

will come in contact with one of the adjusting screws 23 in order to effect rotation of the cylinder 17.

As best shown in Fig. 5, the cylinder 17 is provided with the gear segment studs 24, which project through apertures 25 in the bearer 14, these apertures being larger than the studs. The gear segment 26 is fastened to the studs 24 by means of the screw bolts 10 27. The bed 10 has mounted on one side thereof the rack 28, which is engaged by the gear segment 26 in a manner presently to be described. The shaft 13 is rotated and the bed 10 reciprocated by suitable gearing 15 in the well known manner; but for the sake of simplicity this gearing has not been shown in the drawings.

Having thus described the various parts used in my invention, the operation of the 20 same may now be readily understood.

It will be clear that on account of the clearance which is provided for all parts extending from the cylinder 17 through the bearers 14, the cylinder and the bearers may 25 have relative rotation between them. The paper to be printed is fed to the impression cylinder in the well known manner, and retained thereon by the grippers 19. When the impression cylinder rotates to the starting 30 position the gear segment 26 engages the rack 28, and, since the gear segment is attached directly to the cylinder 17 and not to the bearers 14, the cylinder is brought into proper relation with the bed. In Fig. 1 35 the cylinder is assumed to rotate in a contra-clockwise direction, and after the gear segment 26 engages the rack 28 on continued rotation of the cylinder and continued movement of the bed 10 to the right the 40 paper is printed. If there is not exact correspondence between the movements of the impression cylinder and the bed, this de-

fective action is compensated for by the lost motion between the cylinder 17 and the bearers 14, the permissible amount of such 45 lost motion being controlled by the adjusting screws 23, so that instead of obtaining a blurred impression on the paper and subjecting the form to undue wear the printing operation is perfectly performed.

It will be apparent to those skilled in the art that considerable change could be made in the exact parts which I have described without departing from the spirit or scope of my invention or sacrificing any of its 50 55 advantages.

What I claim is:

In a printing press, the combination of a reciprocatory bed having bearers on its sides, a rotatable bearer adapted to engage each of the bearers of said bed, one of said rotatable bearers having an aperture therethrough, an impression cylinder carried by said rotatable bearers and rotatable with respect thereto, a driving stud projecting 60 from one end of said cylinder through the aperture in one of said rotatable bearers, said stud being smaller than said aperture, adjustable means for controlling the amount of lost motion between said stud 65 and the edges of said aperture, means for actuating said rotatable bearers and said bed, a rack carried by said bed, and a gear segment carried by said cylinder and adapted to engage said rack at a desired stage of 70 the printing operation, whereby said cylinder and said bed are brought into predetermined relation with each other, substantially as described.

CARL HENDERSON.
